UNITED STATES PATENT OFFICE.

JOHN J. THOMAS, OF BALFOUR, NORTH DAKOTA.

WRENCH.

1,407,360.

Specification of Letters Patent. Patented Feb. 21, 1922.

Application filed April 30, 1921. Serial No. 465,734.

To all whom it may concern:

Be it known that I, JOHN J. THOMAS, a citizen of the United States, and a resident of Balfour, in the county of McHenry and 5 State of North Dakota, have invented a new and useful Improvement in Wrenches, of which the following is a full, clear, and exact description.

My invention relates to improvements in 10 wrenches and it consists in the combinations, constructions and arrangements herein described and claimed.

An object of my invention is to provide a 15 wrench that can be adjusted quickly to grip articles of various sizes.

A further object of my invention is to provide a device of the character described that is provided with means operable to releasably and firmly maintain the gripping 20 parts thereof in adjusted positions.

A further object of my invention is to provide a device of the character described that has means for gripping non-circular articles and other means for gripping objects circular in section.

A further object of my invention is to provide a device of the character described that is constructed to occasion the gripping of an object circular in section when the 30 handle of the device is swung in one direction about the object and the release of the object when the handle is swung in the opposite direction.

A further object of my invention is to 35 provide a device of the character described in which the relatively movable co-engaging parts are completely housed so as to be protected from grit and wear and consequently may be maintained in lubricated 40 condition.

A further object of my invention is to provide a device of the character described in which the extent of the space between co-operating jaw members at any adjustment 45 is approximately indicated.

A further object of my invention is to provide a device of the character described that is effective for the purpose intended, not likely to get out of order easily, and thoroughly practical commercially.

Other objects and advantages will appear in the following specification, and the novel features of the invention will be particularly pointed out in the appended claims.

55 My invention is illustrated in the accom-

panying drawings forming part of this application, in which

Figure 1 is a horizontal section through the device,

Figure 2 is a side elevation of the same, 60

Figure 3 is a detail of a jaw member of the device,

Figure 4 is a section along the line 4—4 of Figure 1,

Figure 5 is a section along the line 5—5 65 of Figure 1, and

Figure 6 is a section along the line 6—6 of Figure 1.

In carrying out my invention, I provide a shank 1 having an integral head 2 formed 70 with opposite lateral extensions 3 and 4, constituting jaw members. The shank 1 is non-circular in section and is reduced at 5. The reduced portion 6 is circular in section and is further reduced to define a shoulder 75 7, the end portion 8 thereof being threaded at 9 and constituting a screw. Slidably disposed on the shank 1 is a sleeve 10 formed with integral lateral extensions 11 and 12 arranged to cooperate with the jaw members 80 3 and 4 respectively.

The jaw members 3 and 11 have plane adjacent sides or faces 13 and 14 respectively, adapted for engagement with a non-circular object, such as a nut. The jaw member 4 85 is fashioned with the side thereof facing the jaw member 12 recessed or curved as indicated at 15 so that the jaw member 12 may extend beyond the adjacent edge of its outer end portion 16. The jaw member 90 12 has a guideway 17 therein in which works a guide extension 18 of a jaw piece 19 formed with teeth 20 in the inclined side thereof that faces the recessed portion of the jaw member 4. The jaw piece 19 is held for 95 movement longitudinally with respect to the jaw member 12 by the engagement of a pin 20' carried by the guide member 18 to project through a slot 21 in the wall of the guideway 17.

The adjustment of the sleeve 10 relative to the shank 1 so as to move the cooperating jaw members into desired relative positions is effected by the operation of cooperating alined thimbles 22 and 23, as will be understood from the following disclosure. The thimble 22 has an inwardly offset end portion 24 threaded interiorly at 25 for engagement with the threaded end portion or screw 8 and threaded exteriorly at 26 for engage- 110

ment with the interiorly threaded end portion 27 of the thimble 23. The thimble 23 is further spaced from the threaded end portion 8 by an integral annular extension 28 5 that is threaded interiorly at 29 for engagement with the latter.

The thimble 23 is releasably maintained in adjusted position relative to the thimble 22 by the engagement of a spring pressed 10 ball member 30 with a selected one of four spaced apart substantially hemispherical sockets 31 in the adjacent end wall of the offset portion 24. The ball member 29 is actuated by a spring 32 disposed in a 15 pocket 33 in the end of the annular extension 28.

The thimble 23 is formed with an outwardly offset end portion 34 that is adapted 20 to receive the adjacent end portion of the thimble 22 so that the end of the offset portion 24 is spaced from the adjacent end of the annular extension 28. The thimble 22 has a flange 35 abutting the end of the sleeve 10 and formed with four spaced apart 25 sockets 36 therein. A spring pressed ball member 37 working in an opening 38 through the enlarged end portion of the sleeve 10 engages the sockets 36 selectively and releasably maintains the thimble 22 in 30 adjusted position relative to the sleeve 10. The ball member 37 is thrust toward the thimble 22 by a spring 39 that is maintained in position by a cap screw 40 screwed into the opening 38, as best seen in Figure 5.

The end portion 8 of the shank has the threads thereof cut away at 41 and 42 for the entire length thereof, leaving diametrically opposed segmental threads. The offset 40 portion 24 has the threads thereof cut away at 43 and 44 and the annular extension 28 of the thimble 23 likewise has the threads thereof cut away at 45 and 46. A disk 47 is secured to the end portion 8 as by means of a screw 48. A spring 49 is disposed between the disk 47 and a plug 50 that has a threaded engagement at 51 with the thimble 23 at its outer end, whereby the spring 49 reacts against the disk 47 and tends to move the shank 1 away from the adjacent end of the thimble 22.

From the foregoing description of the various parts of the device, the operation thereof may be readily understood. When 55 the thimbles 22 and 23 are in the position illustrated in Figure 1, the screw 8 is engaged by the threaded segments of the offset portion 24 and the integral extension 28, which are alined. When the thimbles 22 and 60 23 are turned as a unit, through 90 degrees or one-quarter revolution, the threaded portions of the screw 8 will be moved out of engagement with the threaded walls of the offset portion 24 and the integral extension 65 28 so that the shank 1 will be forced in

the direction of its length by the pressure of the spring 49 on the disk 47. Obviously, the head 2 may now be moved toward the adjacent end of the sleeve 10 as desired and will be releasably maintained in adjusted 70 position when the thimbles 22 and 23 are moved as a unit one-quarter revolution to cause the threaded portions thereof to engage the threaded portions of the screw 8. The thimble 23 is normally prevented from 75 turning relative to the thimble 22 on account of the engagement of the ball member 30 with the sockets 31 in the offset portion 24 that is integral with the thimble 22. The thimble 22 is likewise normally held against 80 movement relative to the sleeve 10 on account of the engagement of the ball member 37 with one of the sockets 36. The gross adjustment of the head 2 relative to the adjacent end of the sleeve 10 in order to position the cooperating jaw members approximately as desired, is accomplished by moving the head 2 and the sleeve 10 relatively 85 when the screw 8 has been disengaged by the thimbles 22 and 23. Should a more accurate 90 adjustment be required, the thimble 23 is turned one-quarter revolution relative to the thimble 22. The screw 8 will now be constantly engaged by either the offset portion 95 24 of the thimble 22 or the integral annular extension 28 of the thimble 23 as the thimbles 22 and 23 are turned as a unit to occasion a longitudinal movement of the shank 1.

It is to be observed that the shank 1 is 100 provided with a scale 52 marked thereon adjacent to the head 2 so that a desired adjustment of the outer jaw members relative to the inner jaw members may be accurately accomplished and the extent of the space between cooperating jaw members will be indicated. I prefer to provide graduations having a value of one-eighth inch in the scale 52. Obviously, the scale may be provided with any desired unit.

The device illustrated is a combination 105 wrench adapted for use when it is desired to grip objects either circular in section, as for instance, pipe, or non-circular in section. The cooperating jaw members 3 and 11 may be adjusted to grip non-circular objects, such as a nut. The jaw members 4 and 12 are used in engaging pipe or the like. The latter will be firmly gripped when inserted therebetween and the handle of the device is 110 swung about the jaw piece 19 so that the teeth 20 contact with the work and the jaw piece 19 is moved inwardly. The work will be released when the handle of the device is moved in the opposite direction.

I claim:

1. A wrench comprising a shank having a non-circular body portion and formed to provide a jaw at one end and being circular in section for a part of its length, said cir- 110

- cular sectioned portion being threaded adjacent its end to constitute a screw, the threads being cut away to provide diametrically opposed substantially plane sides extending the length of the screw, a sleeve 5 slidable on the non-circular body portion and formed at one end to provide a jaw adapted to cooperate with the first named jaw, a thimble rotatably mounted on the circular sectioned portion of the shank and abutting the sleeve, said thimble being formed with a plurality of sockets in its end wall contiguous to the sleeve, and a spring 10 pressed ball member carried by said sleeve and engaging said sockets selectively to releasably lock the thimble against rotation relative to the sleeve, said thimble being formed with an inwardly extending offset portion threaded interiorly to engage the screw, the threads of the offset portion being cut away to provide diametrically opposed substantially plane sides extending the length of the offset portion and adapted to register with the plane sides of the screw.
- 25 2. A wrench comprising a shank having a non-circular body portion formed to provide a jaw at one end and being circular in section for a part of its length, said circular sectioned portion being threaded adjacent its end to constitute a screw, and the threads being cut across to provide parallel substantially plane sides extending the length of the screw, a sleeve slidable on the body portion of the shank and being formed at one 30 end to provide a jaw adapted to cooperate with the first named jaw, a thimble disposed on the shank to abut the end of the sleeve and having an inwardly offset portion at its outer end threaded for engagement with the screw, said inwardly offset portion having the threads thereof cut across to provide parallel plane sides adapted to register with the plane sides of the screw, means for connecting the thimble and the sleeve to permit 35 rotation of the former, means for releasably locking the thimble against rotation relative to the sleeve, a second sleeve disposed on the screw to project beyond the end thereof and having an inwardly extending annular portion provided with threads adapted to engage the threads of the screw, the threads of the annular extension being cut across to provide diametrically opposed plane sides adapted to register with the plane sides of 40 the screw, said second named thimble having a threaded connection at its inner end with the adjacent end of the first named thimble and being threaded interiorly at its outer end, cooperating means carried by said 45 thimbles at their adjacent ends for releasably locking the second named thimble against rotation relative to the first named thimble, a disk secured to the outer end of the screw for limiting the slidable movement of the latter relative to the first named
- thimble, a spring disposed in said second named thimble between the outer end thereof and the disk and arranged to react against the latter, and means engaging the second named thimble at its outer end for maintaining the spring in position.
- 50 3. A wrench comprising a shank formed to provide a jaw at one end and being threaded adjacent to its other end to provide a screw, a sleeve slidable on the shank and formed at one end to provide a jaw adapted to cooperate with the first named jaw, a thimble rotatably mounted on the shank and abutting the sleeve, said thimble being formed with a plurality of sockets in its end wall contiguous to the sleeve, and a spring-pressed ball member carried by said sleeve and adapted to engage said sockets selectively to releasably lock the thimble against rotation relative to the sleeve, said thimble being formed with an inwardly extending offset portion threaded interiorly to engage the screw.
- 55 4. A wrench comprising a shank formed to provide a jaw at one end and being threaded adjacent to its other end to constitute a screw, the threads being cut away to form diametrically opposed substantially plane sides extending the length of the screw, a sleeve slidable on the shank and being formed at one end to provide a jaw adapted to cooperate with the first named jaw, a thimble rotatably mounted on the shank and abutting the sleeve, said thimble being formed with a plurality of sockets in its end wall contiguous to the sleeve, and a spring-pressed ball member carried by said sleeve and adapted to engage said sockets selectively to releasably lock the thimble against rotation relative to the sleeve, said thimble being formed with an inwardly extending offset portion threaded interiorly to engage the screw, the threads of the offset portion being cut away to provide diametrically opposed substantially plane sides extending the length of the offset portion and adapted to register at times with the plane sides of the screw.
- 60 5. A wrench comprising a shank formed to provide a jaw at one end and being circular in section adjacent to its other end, said circular portion being threaded adjacent to its end to constitute a screw, segmental portions of the threads of said screw being cut away to provide parallel substantially plane sides extending the length of the screw, a sleeve slidable on the non-circular portion of the shank and being formed at one end to provide a jaw adapted to cooperate with the first named jaw, a thimble disposed on the shank to abut the end of the sleeve and having an inwardly offset portion at its outer end threaded for engagement with the screw, said inwardly offset portion having segmental portions of the threads thereof

2
cut away to provide parallel plane sides adapted to register at times with the plane sides of the screw, means for connecting the thimble and the sleeve to permit rotation 5 of the former, means for releasably locking the thimble against rotation relatively to the sleeve, a second thimble disposed on the screw to project beyond the end thereof and having an inwardly extending annular portion 10 provided with threads adapted to engage the threads of the screw, segmental portions of the threads of the annular ex-

tension being cut away to provide diametrically opposed plane sides adapted to register at times with the plane sides of the 15 screw, said second-named thimble having a threaded connection at its inner end with the adjacent end of the first-named thimble, and cooperating means carried by said thimbles at their meeting ends for releasably 20 locking the second-named thimble against rotation relatively to the first-named thimble.

JOHN J. THOMAS.
